(57) **CLAIM**

The ornamental design for a bending tool for malleable ENT surgical tools, as shown and described.

DESCRIPTION

FIG. 1 is a top perspective view of a bending tool for malleable ENT surgical tools, showing our new design;

FIG. 2 is a bottom perspective view thereof;

FIG. 3 is a left elevational view thereof;

FIG. 4 is a right elevational view thereof;

FIG. 5 is a rear elevational view thereof;

FIG. 6 is a front elevational view thereof;

FIG. 7 is a top plan view thereof; and,

FIG. 8 is a bottom plan view thereof.

The evenly spaced broken lines in the drawings depict portions of the bending tool for malleable ENT surgical tools that form no part of the claimed design. The dot-dash-dot lines in the drawings define the boundary of the claim, it being understood that the dot-dash-dot lines themselves form no part of the claimed design.
